Louis J. Koukal, 402 E. 78th St.,
New York, N.Y. 10021

Filed Oct. 6, 1967, Ser. No. 8,891

Term of patent 14 years

(Cl. D9—277)

FIG. 1 is a front perspective view of a dispensing closure for a bottle or the like showing my new design, with the gate valve in closed position, and wherein a threaded cap form is used;

FIG. 2 is another front perspective view, with the gate valve in open position;

FIG. 3 is a top plan view thereof,

FIG. 4 is a side elevational view thereof,

FIG. 5 is a bottom plan view thereof,

FIG. 6 is a sectional view taken on line 6—6 of FIG. 1,

FIG. 7 is a front perspective of a dispensing closure for a bottle or the like showing another form of my new design, with the gate valve in closed position, and wherein a tapered plug is used,

FIG. 8 is a similar view with the valve gate lowered,

FIG. 9 is another front perspective view, with the gate valve in open position,

FIG. 10 is a side elevational view thereof,

FIG. 11 is a bottom plan view thereof, and

FIG. 12 is a rear elevational view thereof.

I claim:

The ornamental design for a dispensing closure for a bottle or the like, substantially as shown and described.
